CANOE CARRYING YOKE

Maurice H. O'Link, St. Cloud, Minn., assignor to Stearns Manufacturing Co., St. Cloud, Minn., a corporation of Minnesota

Filed Dec. 1, 1961, Ser. No. 67,762

Term of patent 14 years

(Cl. D71—1)

FIG. 1 is a perspective view of a canoe carrying yoke showing my new design;

FIG. 2 is a view in top plan;

FIG. 3 is a view in bottom plan; and

FIG. 4 is a view in side elevation.

The end not shown is substantially the same in appearance as that shown in FIG. 4, and the inner portion of the collar member not shown is substantially the same in appearance as that shown in FIG. 1.

I claim:

The ornamental design for a canoe carrying yoke, as shown and described.
